UNITED STATES PATENT OFFICE

SAMUEL M. DAVIS AND HARRY F. DAVIS, OF BELLWOOD, PENNSYLVANIA

WINDOW BLIND AND CURTAIN FIXTURE

Application filed July 24, 1929. Serial No. 380,672.

This invention relates to window blind and curtain fixtures and has for its primary object an improved device for the support of the window blind and roller and improved means for attaching and detaching the curtain supporting devices.

Another object of this device is to provide a permanent window facing bracket to which the blind roller brackets and the curtain supporting devices are attached, and a further object of the present invention is to provide combined integral blind roller and curtain supports, such supports having definite and fixed means for attaching and detaching the curtain supporting devices.

A still further object of this invention is to provide means for slidably mounting curtain and blind holding fixtures such that the blind and curtains can be readily moved toward or away from the window casing. With these and many other objects in view, which will be more readily apparent as the nature of the invention is better understood, the same consists in the novel combination construction and arrangement of parts as will be hereinafter fully pointed out, illustrated and claimed.

It will be quite readily understood by those skilled in the art to which this invention belongs that the same is susceptible of various changes and modifications without departing from the spirit or scope of the invention, but a preferred and practical embodiment thereof is shown in the accompanying drawings in which:—

Fig. 1 shows a plan view of the blind roller and curtain supports, this assembly being likewise shown for a single window.

Fig. 2 shows side and plan views of one of the combined blind and curtain fixtures supports shown in the assembly view in Fig. 1 of the drawings.

Similar reference numerals refer to similar parts in the drawings.

In carrying out the present invention I provide a primary support designated by the numeral 10 which may be attached to the window facing through the medium of screws, nails, or other fastenings. This primary support 10 is provided with a plu-

rality of slots 11, and as will be observed from Figure 1 is adapted to detachably carry a U-shaped bracket which in turn supports the blind roller 17 and the curtain supports 18, said U-shaped bracket being designated generally by the numeral 22. The blind roller 17 is supported in the downwardly slotted offset arm 23 of the bracket.

From the foregoing it will be apparent that the present construction includes the primary supporting or attaching member 10 adapted to be secured to the center frame, the same including a portion of narrow width and relatively great height disposed in spaced relation to the center frame, and provided with a pair of laterally spaced vertical slots which receive the correspondingly slotted arm portions of the U-shaped bracket member 22. The U-shaped form of the bracket 22 has the advantage of being braced against lateral tilting, or twisting and thus avoids the necessity of employing any auxiliary means for this purpose.

Without further description it is thought that the features and advantages of the invention will be readily apparent.

We claim:—

A combined shade roller and curtain rod support comprising a U-shaped sheet metal bracket inclusive of a pair of spaced arms, means for detachably mounting said bracket on a window frame, and a shade roller supporting formation and a curtain rod supporting formation on said arms, respectively, said shade-roller-supporting formation comprising a member integral with its related arm extending downwardly therefrom and bent first laterally from said arm and then forwardly to lie in a plane parallel to said arm below the latter.

In testimony whereof we affix our signatures.

SAMUEL M. DAVIS.
HARRY F. DAVIS.
